UNITED STATES PATENT OFFICE.

MAXEY JACKSON, OF TOPPENISH, WASHINGTON.

RAILWAY-CROSSING.

1,206,711.

Specification of Letters Patent. Patented Nov. 28, 1916.

Application filed March 16, 1916. Serial No. 84,678.

To all whom it may concern:

Be it known that I, MAXEY JACKSON, a citizen of the United States of America, residing at Toppenish, in the county of

5 Yakima and State of Washington, have invented certain new and useful Improvements in Railway-Crossings, of which the following is a specification.

This invention relates to improvements in 10 railways, and more particularly to railway crossings.

The primary object of this invention is to construct a railway crossing to provide continuous rails and thereby eliminate the usual 15 noise caused by the wheels of a car passing over the spaced ends of rails of the tracks now in use.

A further object of the invention is to provide means for simultaneously shifting 20 the rails of one track section, into or out of engagement with the rails of the other track section.

A still further object of the invention is to provide means of this character which 25 will be simple, inexpensive, efficient and automatic in its operation.

In the drawings: Figure 1 illustrates a plan view of a railway crossing embodying 30 my invention. Fig. 2 illustrates a detail view in section of adjacent rail sections. Fig. 3 illustrates a side elevational view of the crossing. Fig. 4 illustrates a sectional view of a rail with an operating arm secured thereto. Fig. 5 illustrates a sectional view, 35 and Fig. 6 illustrates a sectional view of a rail together with its supporting plate.

Referring more particularly to the drawings, the numerals 5 and 6 indicate rails of 40 a railway track, extending in one direction and the numerals 7 and 8 indicate rails of a track extending at right angles to the first mentioned rails.

Forming continuations of the rails 5 and 45 6, but independent thereof, are the sectional movable rail members 9 and 10, supported on the movable plates 10', and bolted thereto by suitable securing means 11', said plates being supported on the plates 12' and held 50 thereon by the usual spikes 13', which extend along the side of the plates 12' and into the usual ties 14' forming a part of the track

structure. One end of each of said movable sections 9 and 10 is beveled as at 11", whereby the beveled ends may be brought together 55 to form continuous rails.

Extending at right angles to the movable rail sections 9 and 10 are the movable rail sections 11 and 12, these sections are also beveled as at 13 to form continuous rails 60 when the beveled ends 13 are moved to engage each other. The movable rail sections 11 and 12 are also supported on movable plates 15 which in turn are movably supported on plates 16', the same being also 65 secured to the usual railway ties 14', in a manner similar to the way in which the movable sections 9 and 10 are secured.

The beveled ends of the movable rail sections are provided with transverse alining 70 openings 16' through which extend operating levers 17, the walls of said alining openings being curved to provide camming faces. Each operating lever 17 has a pivot pin 18 extending downwardly therefrom through 75 the elongated slots 19, formed by the co-operating notches 19' provided in the movable plates 10' and 15, and into the respective plates 12' and 16.

Each of the operating levers 17 is provided at its extremity with an opening 20 through which extends a pin 21, these pins also extending through alining openings 22 and 23 provided in the bars 24, 25, 26, and 27 constitute efficient means for connecting 85 the operating levers 17 whereby movement of one of said levers produces relative movement of the remaining levers to accomplish the moving of the movable rail sections.

Adjacent the respective openings 20 and 90 extending vertically through each of the operating levers 17 are openings 24', which receive the depending ends 28 of the rods 29 which lie adjacent the rails of the tracks, and are connected at their opposite ends 95 with the lower end of the bell-crank levers 27, the opposite ends of the bell-crank lever extending in proximity with the upper or tread portion 28' of the rails 5, 6, 7, and 8 or in a position to be engaged by the flange 100 of the wheels of a car passing thereover.

As already shown by Fig. 4, the bell-crank levers 27, are pivotally connected to the supporting blocks 27' by pivot pins 28'',

said blocks 27' being rigidly connected to the rails and supporting the bell-crank levers 27, in a plane with the sides of the rails. It might be further stated that the plates 10' 5 are provided with inclined notched portions 30' which receive the spikes 13', the inclined notched portions 30' of one side of the rails extending in a direction directly opposite from the direction in which the inclined 10 notches of the opposite side of the rails extend, whereby movement of the movable rail sections is restricted, due to the engagement of the spikes 31 with the straight edges 32 of the notched portions 30'.

15 The operation of the device is as follows: As shown by Fig. 3, the operating arm 27 has been engaged by the flange of a wheel of a railway car, which engagement resulted in the depression of one end of the arm 27 20 and the rocking thereof, thereby operating the operating levers 17, which impart a relative movement to the movable rail sections, with the result that the movable rail sections of one track are moved to provide continuous unbroken rails, as shown in said Fig. 3, while the movable rail sections of the other track are simultaneously moved out of engagement with the rails of the first mentioned track, as rails 11 and 12 of Fig. 1 25 depict the movement of said movable rail sections being limited, due to the construction of the inclined notched portions 30' and the relation of the spikes 13' thereto. It is of course understood that a car or cars moving over the rails of the other track section, 30 will operate to move the movable rail sections in a manner opposite to that just described.

Although I have described the preferred 40 embodiment of my invention, I may desire to make such changes in the construction, combination and arrangement of parts thereof, as do not depart from the spirit of the invention and the scope of the appended 45 claims.

What I claim is:

1. In a railway crossing, stationary rail sections, movable rail sections, operating levers extending through the adjacent ends 50 of the movable rail sections, bars for connecting the operating levers, means positioned adjacent the stationary rail sections and adapted to be engaged by the flange of a car wheel passing thereover, for operating 55 the operating levers simultaneously for moving the movable rail section.

2. In a railway crossing, stationary rail sections, movable rail sections arranged in pairs and coöperating with the stationary 60 rail sections to form continuous tracks, each of the movable rail sections having a beveled extremity, an operating lever connected with the beveled ends of each pair of movable rail sections, means connecting the operating

levers whereby they will operate the movable 65 rail sections simultaneously, operating rods positioned adjacent the rails of the stationary rail sections, and operating arms connected to the operating levers, said arms lying in a plane to be engaged by the flange 70 of a car wheel passing thereover, for rocking the arms to impart a horizontal movement to the operating rods for moving the movable rail sections.

3. In a railway crossing, stationary rail 75 sections, movable rail sections coöperating with the stationary rail sections, movable plates for supporting the movable rail sections, said movable rail sections having transverse openings, operating levers extending 80 through the openings, operating arms supported adjacent the rails of the stationary rail sections, means for connecting the operating levers and operating arms whereby movement of the operating levers produces 85 a relative movement of the operating arms.

4. In a railway crossing, stationary rail sections, movable rail sections, having beveled coöperating ends, movable supporting plates having coöperating beveled 90 ends supporting the respective movable rails, operating levers connected with the beveled ends of each of the movable rail sections, a pivot pin for the operating levers, the supporting plates having coöperating 95 notched portions forming guide-ways for the pins of the operating levers, means for connecting the operating levers, and means for causing the operating levers to operate simultaneously, for moving the movable rail sections into and out of engagement with the stationary rail sections.

5. In a railway crossing, stationary rail sections, and movable rail sections, each movable rail section comprising a plate, 105 movable supporting plates for each movable section, rails carried by the movable supporting plates and rigidly secured thereto, said rails having overlapping beveled ends provided with transverse alining openings, 110 operating levers extending through the alining openings for moving the rails simultaneously and said movable supporting plates having means coöperating with means on the operating levers for holding the operating levers in position, and means for operating the operating levers simultaneously.

6. In a railway crossing, stationary rail sections, movable rail sections interposed 120 therebetween and arranged in coacting pairs with overlapping end portions, the overlapping end portions of said movable rail sections being provided with cam portions, and operating levers coöperating with the 125 cam portions of the movable rail sections.

7. In a railway crossing, stationary rail sections, movable rail sections interposed

therebetween and arranged in pairs adapted to be disposed in alined relation for connecting the stationary rail sections, the adjacent ends of the movable rail sections of each pair being overlapped and formed with registrable openings having cammed vertical walls, and a lever extending through the

openings of each pair for operating on the cam portions of said movable rail sections to move the latter toward and from the stationary rail sections. 10

In testimony whereof I affix my signature.

MAXEY JACKSON.
